UNITED STATES PATENT OFFICE.

AUGUST TEGOLI, OF SANTA ROSA, CALIFORNIA, ASSIGNOR OF ONE-THIRD TO CHARLES E. BERTOLI AND ONE-THIRD TO LIBRO TANTIMONACO, BOTH OF SANTA ROSA, CALIFORNIA.

DRYING APPARATUS.

1,135,556.

Specification of Letters Patent. Patented Apr. 13, 1915.

Application filed September 15, 1914. Serial No. 861,615.

To all whom it may concern:

Be it known that I, AUGUST TEGOLI, a subject of the King of Italy, residing at Santa Rosa, in the county of Sonoma and State of California, have invented certain new and useful improvements in Drying Apparatus, of which the following is a specification, reference being had to the accompanying drawings.

10 My invention relates to certain new and useful improvements in drying apparatus and especially to apparatus designed for drying pastes, such as macaroni, etc., and has for its object the production of an apparatus which will facilitate, hasten and regulate the drying of pastes or other materials, and produce better qualities and at reduced cost.

It has also for its object to prevent souring and molding, to preserve the original color, to avoid breakage as a result of too rapid initial drying primarily, and to finish a comparatively large batch in a minimum time.

25 Another object in view is to dry paste so thoroughly as to prevent weevils from attacking it as is often the case when dried in the usual manner.

With these and other objects in view my invention consists in the construction and arrangement hereinafter more fully described.

In order that those skilled in the art to which my invention appertains may know how to make and use my improved drier I will proceed to describe the same referring by numerals to the accompanying drawings in which—

Figure 1 is a front view of an apparatus embodying the features of my invention, Fig. 2 is a horizontal section broken away and showing at one end a plan view of fan chambers, and at the other end a plan view of drawers. Fig. 3 is an enlarged vertical section on the line $a-a$, of Fig. 2; Fig. 4 is a detail vertical section showing the drawers and supporting brackets, and Fig. 5, a fragmentary section of the removable drawer slide bars.

50 Similar reference numerals indicate like parts in the several figures of the drawings. 1 represents what may be designated as an air tight heating chamber or compartment preferably constructed of vertically

arranged boards, which chamber is surrounded by steam or hot water pipes 2 having inlet valve (not shown) at the left and an outlet valve 3 at the opposite end in order that a proper circulation may be established to have radiated heat surrounding the compartment.

A frame consisting of preferably iron horizontal bars 4 and vertical bars 5 extends above the heating room 1 and the arrangement of these bars produce drawer spaces 6 adapted to receive drawers 7 which as shown in Fig. 4 slide upon horizontally disposed guides 8 secured in any suitable manner to the vertical bars 4, so that the drawers may be readily located and removed. These drawers are each composed preferably of a frame with woven wire bottom, the mesh of the wire used being according to the different sizes of the bodies to be treated in the apparatus.

75 In the construction illustrated in Fig. 1 provision is made for thirty-two drawers. The central drawer compartments being occupied by sixteen drawers, the eight drawer spaces each side of the center I have shown as unoccupied but ready to receive sixteen drawers or a number equal to the central drawer spaces, as will be hereinafter more fully referred to. Beneath the eight drawers at each end of the apparatus is a longitudinal shaft 9 mounted in journal bearings

10. The inner end of this shaft is provided with a rotary fan 11, and at the opposite end with a belt pulley 12 and an idler 13. This fan may be designated a blast fan and causes a current which passes upwardly through any drawers located in the eight spaces at the left of the apparatus and out at the top as indicated by the arrows in Figs. 1 and 2. The same arrangement of shaft, fan and pulleys is made at the opposite end of the apparatus and currents of air are likewise driven upward through the eight drawers to be located at that end and out as also indicated by the arrows; in other words the two end compartments and their equipments are duplicates. The fans in these compartments are driven by belts 14 from pulleys 15 keyed to a longitudinal shaft 16 which is driven from any suitable source of power. The fans 11 are designed to be rotated at a comparative low speed in order that the material being treated may not be

dried so rapidly as to produce cracks or breakage.

The end chambers in which the upward air currents are produced are separated from the middle chamber by suitable vertical partitions 17 having an opening therein constituting a wind trunk.

The central chamber beneath the sixteen central drawer spaces is provided with a transverse shaft 19 mounted in suitable bearings 20 and is provided at the outer or rear extremity with a driven pulley 21, and an idler 22 and has secured to it in an opening in the back wall of the chamber an exhaust fan 23, which produces a down draft from the top of the center of the machine and through the sixteen drawer spaces as indicated by the arrows, and out through the back of the apparatus near the bottom thereof and through a wind trunk 24.

All of the fans are in a well known manner made adjustable as to angle or pitch. The exhaust fan shaft is driven through the medium of a pulley 25 on the power shaft 16 and a belt 26 in an obvious manner. It is to be understood that the fan 23 is designed to create a relatively much higher wind current than is created by either of the fans 11, and to that end the fan 23 may have its blades adjusted to a greater angle than the blades on the fans 11, or may have a greater number of blades, or may be driven at a higher speed. In the actual operation of my invention, for instance, the fan 23 will preferably have eight blades driven at a thousand revolutions per minute, while the fans 11 will have six blades driven at 800 revolutions per minute.

The fan shafts and bearings are all suitably lubricated by oil cups 27.

Along the front of the apparatus supported on suitable means shown in dotted lines at Fig. 2 is a front walk 28 for the operator of the apparatus and so that he can conveniently manipulate the series of drawers.

In using my improved drier the material to be acted upon is placed in as many of the drawers as may be necessary and these drawers are located in the drawer spaces over the end chambers and the speed and pitch of the fans in these compartments are so regulated as to produce a moderate upward current of heated air which is continued for a very few minutes, and the material is thus dried in such manner as not to crack the surface or change the color; these drawers are then removed and placed over the middle chamber and subjected to the action of down currents of greater volume and velocity than the air currents previously used at the end chambers which conduces to very rapid and complete drying, and as the material rests upon the woven wire bottoms of the drawers and the air currents are downward it will be

readily seen that the material is not tumbled and tossed about as would be the case with upward currents of the same velocity.

The hot water or steam pipes at the lower portion of the apparatus may be employed or not as occasion demands but it will be obvious that with their use, the drying operation may be conducted in any kind of weather without danger of molding.

With my apparatus the air which passes through either of the end chambers is drawn from the middle chamber, and as a consequence is heated or warmed before its passage up through the pastes being dried, whereas the air which passes downward through the paste supported above the middle chamber is fresh air unheated and exerting, therefore, a rapid cooling action upon the paste. The passage of the air down through the paste supported in the middle set of drawers tends to somewhat cool this air and also warm it so that this air in its passage up through the paste supported above the end chambers will not exert such a rapid drying action or such a rapid cooling action as it otherwise would do. The action of the air therefore is not only modified by the rapidity and strength of the blast, but is also modified by the action of the heating pipes and by the initial passage of the air from the exterior of the casing into the middle compartment.

It will be seen that in the use of my improved apparatus it is not necessary to employ high class or expert labor, such as is absolutely necessary according to the present process of drying as success in such cases depends absolutely upon the skill and experience of the operator.

With an apparatus of the proportions shown and accommodation for thirty-two drawers, it will be seen that when the material in the eight drawers over each end chamber has been partially dried as explained, the sixteen drawers are then placed in the sixteen drawer spaces over the middle chamber and while the final treatment is being made the end drawer spaces may be again filled with drawers for the initial treatment, so that it will be apparent that a very large amount of material may be treated in a comparatively limited period of time, thus making the drying process less expensive in time and labor than is the case in the ordinary manner of drying.

Many variations may be made in the mere details of construction and arrangement of the apparatus without departing from the spirit of my invention which resides in providing for the partial and slow drying of the material at one or more compartments, through the medium of blast currents, and the subsequent and final action of rapid exhaust currents of greater volume.

Having described the construction and

operation of my improved paste drier and its advantages what I claim as new and desire to secure by Letters Patent, is:—

1. A drier having a middle and lateral 5 chambers, the former provided with an exhaust fan, and the latter with blast fans, a series of drawers having bottoms adapted for the passage of air, arranged in drawer spaces over the several compartments, and 10 means for operating the several fans, substantially as and for the purpose set forth.

2. In a drying apparatus such as described and comprising a middle and lateral chambers provided respectively with an exhaust, 15 and blast fans and means for rotating the fans, perforate drawers, said drawers having perforate bottoms and being arranged in drawer spaces over the respective fan equipped chambers, said chambers provided 20 with means for heating the air therein, substantially as and for the purpose set forth.

3. In a drying apparatus such as described, comprising a plurality of closed chambers, with a series of perforate bottom 25 drawers arranged in drawer spaces over the said chambers, means for producing upward air blast currents in certain chambers and downward exhaust currents through certain other chambers substantially as and for the 30 purpose set forth.

4. In a drying apparatus such as described, comprising a multiplicity of chambers provided with fans for producing wind currents, and a series of drawers removably 35 arranged in drawer spaces over the said chambers, a foot board arranged in front of the apparatus substantially as and for the purpose set forth.

5. A drying apparatus such as described 40 comprising two end chambers and one middle chamber, with fans mounted therein upon rotary shafts having belt pulleys at the outer extremities, a longitudinal power shaft having pulleys thereon, and belts leading from said pulleys to the pulleys upon the fan shafts, substantially as shown and described.

6. A drying apparatus comprising a main chamber and a lateral chamber opening 50 thereinto, means for supporting articles to be dried in superposed relation in conjunction with either one of said chambers, means for drawing air into the first named chamber through the articles supported in conjunction therewith, and means for drawing air from the first named chamber into the second named chamber and forcing said air outward therefrom through the articles supported in conjunction therewith.

60 7. In a drying apparatus, a main chamber, and a lateral chamber, both of said chambers being open on one side, means for

supporting articles to be dried in conjunction with the open sides of both of said chambers, means for causing a relatively 65 powerful current of air to pass into the main chamber through the articles supported in conjunction therewith, and means for causing a relatively less powerful current of air to pass from said main chamber into the lateral chamber and outward through the open side thereof and through the article supported in conjunction therewith.

8. A drying apparatus comprising a main chamber and a lateral chamber connected 75 thereto, both of said chambers having open tops, a series of superposed drawer supports mounted above the open tops of both of said chambers, a plurality of drawers having perforate bottoms adapted to be disposed in 80 said drawer supports in superposed relation to either one of said chambers, a suction fan disposed in the main chamber, a trunk wherein said fan is mounted opening into the outer air, said fan acting to draw the 85 current of air downward through the articles supported above the main chamber and to eject said air out through the trunk, and a fan mounted to force air from the main chamber into the lateral chamber and out 90 through the open top thereof, said fan having less power than the first named fan.

9. In a drying apparatus, a rack formed to provide a plurality of drawer compartments, drawers interchangeable in said compartments, means for drawing air downward through certain of said racks and through the drawers mounted thereon, and means for forcing heated air upward 95 through certain other of said racks and the 100 drawers mounted thereon.

10. In a drying apparatus, a casing including a main compartment and a lateral compartment, both of said compartments being open at their upper ends, a drawer 105 rack supported upon said casing above said compartment and formed to support a plurality of drawers, drawers interchangeably supported upon said racks, a wind trunk extending outward from the main compartment, a suction fan mounted therein, a fan mounted between the main compartment and the lateral compartment and drawing air from the main compartment into the lateral compartment and forcing it out through the 110 open top thereof, and means for heating the air within the main compartment.

In testimony whereof I hereunto affix my signature in the presence of two witnesses.

AUGUST TEGOLI.
